UNITED STATES PATENT OFFICE.

AUSTIN C. EVANS, OF SPRINGFIELD, OHIO.

FERTILIZER-DISTRIBUTER FOR SEED-PLANTERS.

SPECIFICATION forming part of Letters Patent No. 295,528, dated March 25, 1884.

Application filed August 29, 1883. (No model.)

To all whom it may concern:

Be it known that I, AUSTIN C. EVANS, a citizen of the United States of America, residing at Springfield, in the county of Clark and State of Ohio, have invented certain new and useful Improvements in Fertilizing-Distributors for Seed-Planters, of which the following is a specification, reference being had therein to the accompanying drawings.

10 My invention relates to fertilizing-distributors for seed-planters.

My invention consists, first, in the construction of the fertilizer-hopper with a wire screen therein, to prevent any lumps or foreign substances from getting into and obstructing the dropping devices, as the screen wholly prevents anything but the finer particles passing through it, thus rendering the fertilizer substance better adapted for dropping or sowing 20 than when used in the ordinary fertilizer-hopper; second, in the incasement of the rotating shaft which extends through the fertilizer-hopper for driving the discharge-wheel, whereby the fertilizer substance is prevented from getting into the bearings of the same, and thus stopping the movement of the sowing devices; third, in the manner of retaining the connecting revoluble shaft and its gearing in adjustment.

30 Two sheets of drawings accompany this specification—Sheet 1, with Figures 1 and 2, and Sheet 2, with Figs. 3 to 14, inclusive.

Fig. 1 is a side elevation of a two-horse seed-planter with my improved fertilizing-distributor applied thereto. Fig. 2 is a top view of the same. Fig. 3 is a front elevation of the fertilizer-hopper with the actuating mechanism on the outside of the same. Fig. 4 is a rear elevation of the same with a portion of the shield broken away to exhibit the discharge-wheel and feed-disk. Fig. 5 is a view of the inside of the fertilizer-hopper with the screen removed. Fig. 6 is a side elevation of the same. Fig. 7 is a top view of the screen, 45 which fits into the hopper about three inches from the top. Fig. 8 is a view of the lever and its attached pawls, shown on the front of the hopper in Fig. 3, as seen from the reversed side. Fig. 9 is a top view of the slide-bar and 50 drive-frame bolted thereon, which latter is provided with a square notch on its rear side, en-

gaging with the top end of the pivoted lever seen on the front of the fertilizer-hopper in Fig. 3, for actuating the devices therein. Fig. 10 exhibits face and front views of the ratchet 55 and stop wheel on the front end of discharge-wheel shaft outside of the hopper, over which the actuating-lever is pivoted. Fig. 11 shows side and end views of the connecting revoluble shaft, the part shown being the section 60 having the gearing thereon; also the sleeve in which its end is pivoted. Fig. 12 is a view of the pivotal end of the shaft seen in Fig. 11. Fig. 13 exhibits side and edge views of the staple-shaped key or pin which retains the 65 shaft in adjustment. Fig. 14 is a cross-section of the discharge-wheel shaft and the casting inclosing the same.

A is the fertilizer-hopper, which is of the usual square tapering form, but is made much 70 longer than ordinary hoppers, extending down almost to the lower end of the seed-tube. It is supported upon the horizontal bracket-irons a^2 , which extend directly backward from the main cross-bar of the planter j , and are bolted 75 to either side of the hopper. These bracket-irons have their rear ends broadened and T-shaped to support the hopper firmly.

The fertilizer-distributing devices consist of a dropping-disk rotating within the hopper, the 80 teeth of which pass outside at the rear side of the same, near the bottom, and a driving and discharge wheel, also on the outside of the hopper, on the end of the shaft g , which extends through the same, said discharge-wheel engaging with the teeth of the dropping-disk, as 85 shown in Patent No. 280,360, to A. C. Evans, July 3, 1883, "fertilizing attachment for corn-planters."

The actuating devices consist of a curved 90 toothed ratchet-wheel on the opposite end of the shaft g from the discharge-wheel f on the front side of the hopper, and a peculiar-shaped vertical lever, which extends from the top to near the bottom of the hopper, and is pivoted 95 near its middle part over the ratchet-wheel upon a journal extending horizontally from the front middle line of the hopper. It is flat from the journal b downward, and has two lateral arms, c^2 and c^3 , extending therefrom 100 outward, arm c^2 being below the arm c^3 . A pawl is pivoted upon a horizontal pivot upon-

the inner side of each of these arms, the engaging ends of which extend to the middle longitudinal line of the lever, and engage with the teeth of the ratchet-wheel C' on the end 5 of shaft g, which latter extends through the front side of the hopper. Pawl c' is pivoted to the inner side of the upper arm, c', of the lever, and its short tail end oscillates between stops i' i', extending inward from the end of 10 the arm, across the line of the same, above and below the tail of the pawl. The lower arm, c'', extending in the opposite direction, has a reversed pawl, c, pivoted thereto, having a weighted rear end. The rear extension 15 of this pawl also oscillates between stops i i' on the end of arm c''. Both pawls engage with teeth e' of the ratchet-wheel C', rotating shaft g, and causing the wheel f to drive the disk h as the lever C is oscillated toward 20 either side, as seen by the dotted lines, Fig. 3. The journal b, on which lever C is pivoted, extends from the plate b', seen bolted upon the front of the hopper A under C. A segment, b'', extends outward from plate b', having 25 a tooth, 1, at either end, (see Figs. 3 and 5,) between which lever C oscillates, and which arrests the movement of the latter at the end of each throw. When lever C is moved to the right or left, motion is communicated 30 to the ratchet-wheel C' by pawls c and c' engaging with its teeth e', and the movement of C' is arrested at each throw of the lever by stops e, (seen projecting from its front side, Figs. 3 and 10,) which come in contact with 35 stops 2, (seen on the inner side of C, projecting above pawl c and below pawl c' from arms c' and c'', in Fig. 8,) stops or lugs e on ratchet-wheel C' striking each of the stops 2 on lever C alternately at the end of each movement. 40 In the view Fig. 3, ratchet-wheel C' revolves from left to right. The top end of stem d' of lever C engages with notch n in the rear side of drive-frame E, (which latter is bolted to the drive-bar D,) and motion is thereby 45 communicated to the lever and dropping devices by the hand-lever, in the usual manner, being connected with the latter.

By the use of the long hopper A, and the intermediate lever, C, and its operative pawls, the 50 dropping devices of the fertilizer are brought much nearer to the ground and the fertilizer-dust dropped with more accuracy, and, as a much shorter discharge-tube can be used, the lodgment of the fertilizer-dust therein is obviated. A hollow casing of cast metal, G, as 55 seen in Figs. 5 and 14, of cuneiform shape in its cross-section, is used to cover the shaft g with its longitudinal angle on the top side. This casing completely covers and protects the 60 shaft and its bearings from the fertilizer.

The screen a is seen in Figs. 2 and 7. In 65 the latter figure it is shown enlarged. It is constructed of crossed or interwoven wires supported in a frame. It is placed about three inches below the top of the hopper, and the fertilizer substance, after being broken up, is poured upon the top of it, and the finer dust

particles only pass down through it, while the coarser lumps are left on the screen, and can be afterward broken up with the hands. As 70 fertilizer compounds containing volatile salts absorb dampness and become hard, the advantage of using the screen will be seen. The screen a rests on cleats nailed to the inside of the hopper-box. 75

The adjustable shaft H, which connects the drive gear-wheel F with the dropping devices when the machine is operated automatically, has two pinions, n' and n'', on its gear-section, which latter is adapted to be shifted endwise 80 through the sleeve h' in engaging either of those pinions. Its pivotal end, as seen in Fig. 12, is circumferentially grooved at k k, to allow the key k' to be inserted through holes in the sleeve-piece h' and across the shaft through groove k. A small split pin, p, is inserted 85 through a hole in the end of one of the limbs of h', to prevent the key from slipping out, Figs. 11 and 13. The key is withdrawn to shift the shaft in changing the drop to a longer 90 or shorter distance. To protect the discharge-wheel f and dropping-disk h from dirt that may be thrown off the wheels of the planter, a sheet-metal shield, d', is used to cover them. This has its upper end nailed to the hopper 95 above f, and extends down over the upper edge of spout s, being bent near the top end, as seen in Fig. 6.

I claim as my invention—

1. In a fertilizing attachment for a two-horse 100 corn-planter, the combination, with the fertilizer-hopper and the sowing devices in the bottom of the same, of a fixed screen inclosed within said hopper over said sowing devices, for the purpose of preventing lumps of the fertilizer 105 substance from getting into and obstructing the movement of said sowing devices.

2. In a fertilizing attachment having its dropping-disk driven from a shaft extending through the hopper, and having a ratchet-wheel on its outer end, the combination therewith of a vertical oscillating lever pivoted over said ratchet-wheel, provided with pawls adapted to engage the teeth of the latter, and having its top end engaged with a notch in the drive-frame on the slide-bar, whereby an oscillating movement is given to said lever, communicating an interrupted rotary motion to the dropping devices, substantially as set forth. 115

3. The combination, with the dropping devices and the ratchet-wheel on the outer end of the driving-shaft, having lugs extending therefrom, of the pivoted oscillating lever formed with lateral arms having pawls pivoted thereon, engaging the teeth of said ratchet-wheel, and provided also with a stop on each of its arms, adapted to engage with the lugs on the ratchet-wheel at each throw of said lever, as and for the purpose set forth. 120

4. In a fertilizing attachment for a seed-planter, a vertical lever pivoted upon the front of the hopper between the slide-bar and the dropping devices, having lateral arms extending therefrom and provided with pawls and 130

stops, engaging with the teeth and lugs of a ratchet-wheel on the end of the driving-shaft of said dropping devices, said lever being engaged with and operated by the slide-bar, substantially as and for the purpose set forth.

5. The combination, with lever C, having the lateral arms c^2 and c^3 , provided with stops i and i' on the ends of the same, of the pivoted pawls c and c' , having a tail extension between the stops, which latter govern the movement of said pawls and prevent their disengagement from the teeth of the ratchet-wheel.

6. The combination, with the rotating shaft extending through the hopper for driving the dropping devices in the latter, of the hollow metal casing extending from one side of the hopper to the other over said shaft, to protect the bearings of the latter from exposure to the fertilizer substance, as set forth.

15 7. In an adjustable connecting-shaft having a series of gears thereon for changing the drop,

the combination therewith of a series of grooves corresponding with the number of pinions, and a key for securing said shaft in adjustment, extending through the sleeve with- 25 in which it is pivoted, and adapted to engage the groove corresponding with the engaging pinion.

8. In a two-horse corn-planter having a fertilizer attachment, a shield attached to the outside of the fertilizer-hopper over the discharge-wheel, between the covering-wheel and the discharge-spout, whereby dirt is prevented from dropping from off said covering-wheel into said discharge-spout with the fertilizer. 30 35

In testimony whereof I affix my signature in presence of two witnesses.

AUSTIN C. EVANS.
